S. CORTESE

THREAD CUTTER FOR SEWING MACHINES

Filed June 3, 1926

UNITED STATES PATENT OFFICE.

SAM CORTESE, OF DUNSMUIR, CALIFORNIA.

THREAD CUTTER FOR SEWING MACHINES.

Application filed June 3, 1926. Serial No. 113,507.

This invention is an attachment for shoe-sewing machines and has for its object the provision of simple, inexpensive and efficient means whereby the thread may be 5 easily and rapidly cut after the sewing operation has been completed. The invention provides a thread cutter which may be applied to the shuttle arm of a sewing machine without requiring any substantial 10 structural change in the arm and without modifying the operation of the working parts of the sewing machine in any manner. The invention is illustrated in the accompanying drawing and will be hereinafter 15 fully set forth.

In the drawing:

Figure 1 is a perspective view of a portion of a shoe-sewing machine having my improved thread cutter applied thereto;

20 Fig. 2 is a bottom plan view of the attachment;

Fig. 3 is an enlarged perspective view showing one end of the plate;

25 Fig. 4 is an enlarged central longitudinal section of the plate.

In the drawing, the reference numeral 1 indicates the arm of the sewing machine in which the shuttle and bobbin are mounted and operate, 2 designates the needle and 3 the presser foot, these parts being shown in a more or less conventional manner and being of the usual construction and arrangement. In carrying out my invention, I provide a plate 4 which is narrow and of such 35 length that it will fit upon the arm 1 adjacent the end thereof without projecting excessively beyond the sides of the arm. The plate is provided at its center with an opening 5 through which an attaching screw 6 40 may be inserted into the arm whereby to secure the plate in place and permit it to be readily turned so that either end may be disposed over the shuttle as may be desired. The ends of the plate are substantially 45 arcuate, as indicated at 7, and adjacent each end is an opening 8 which provides for the passage of the needle 2 in the operation of sewing. Near each end there is also provided a second opening 9 through 50 which a stud or pin, indicated at 10, may be inserted into a socket provided therefor in the arm 1 whereby the plate will be held against turning when in use. It will be understood that the stud or pin 10 is inserted through that opening 9 which, in

either position of the plate, is at the inner end thereof. On the under side of the plate 4 are formed grooves 11 which accommodate the shuttle and permit the plate to be set down over the shuttle so that the needle 60 will cooperate therewith in the same manner and with the same efficiency as if the attachment were not provided. At one end the plate 4 is cut away or reduced, as shown at 12, to provide an overhanging flange or 65 lip 13 and in the said lip is a slit or notch 14, the walls of which are sharpened to produce cutting edges whereby, if the thread be engaged in the said slit or notch, it will be readily severed. At the opposite end of 70 the plate, there is also provided a cutter, and this cutter is in the form of a somewhat resilient curved tongue 15 extending around the end of the plate within a recess 75 formed therein to accommodate the tongue, the tongue being secured at one end upon the edge of the plate, as shown at 17. It will be readily noted upon reference to Figs. 1 and 3 that the end of the tongue is free of the plate, although the 80 tongue fits closely to the arcuate edge of the plate and a thread may be easily engaged between the tongue and the plate and drawn under the tongue so as to be cut, it being particularly noted, more especially 85 upon reference to Fig. 4, that the lower edge of the tongue is beveled or otherwise formed into a cutting edge.

The ends of the plate define arcs of different diameters so that either end may be 90 disposed over the shuttle accordingly as the shoe being sewed is larger or smaller. The shoe is sewed in the usual manner and, when the sewing is completed, the presser foot is raised in the customary manner and 95 the shoe withdrawn from the arm 1 and, at the same time, given a slight lateral movement so that the thread will be carried into the slit or notch 14 or against the tongue 15, as the case may be, and thereby severed. The cut of the thread will be close to the shoe and a sufficient length of thread will 100 be left to be easily engaged when another shoe is to be sewed but there will be no waste of thread nor loss of stitches nor 105 breaking of the thread as is now a frequent occurrence. The attachment eliminates the use of a separate knife for cutting the threads which knife is frequently displaced or lost. Consequently, there is no time 110

wasted in searching for lost tools when the workman is employed at a machine equipped with my attachment.

Having thus described the invention, I claim:

1. A thread-cutting attachment for sewing machines comprising a plate provided adjacent its ends with needle openings, means for pivoting the said plate upon the shuttle 10 arm of a sewing machine, means to be engaged with one end of the plate and the shuttle arm of the sewing machine to prevent movement of the plate, and knives at the 15 ends of the plate disposed transversely thereof.

2. A thread-cutting attachment for sewing

machines consisting of a plate constructed to be secured upon the shuttle arm of a sewing machine and provided with needle openings adjacent its respective ends, one end of the plate being reduced on its under side to form an overhanging lip and provided in said lip with a transversely disposed notch, the walls of which form cutting edges and the other end of the plate being recessed, and an arcuate tongue secured to the edge of the plate and conforming to said recess, the lower edge of the tongue forming a cutting edge. 20 25

In testimony whereof I affix my signature.

SAM CORTESE. [I. S.]
